8 Sheets-Sheet 1

The diagram illustrates the timing sequence for printing the letter 'N'. It shows two main groups of pulses: 'PRINTING' and 'WORKING SPACING'.

- WORKING SPACING:** This occurs at the beginning of the sequence. It consists of a **STOP INTERVAL** (indicated by a hatched bar), followed by a **START** pulse, and then a **PRINT (LETTER 'N')** pulse.
- PRINTING:** This occurs in two stages. The first stage consists of a **STOP** pulse, followed by a **START** pulse, and then a **PRINT (LETTER 'N')** pulse. The second stage consists of a **STOP** pulse.
- ISOCHRONOUS CODE SIGNAL:** This is a continuous signal shown as a hatched bar between the two main groups.
- SELECTING IMPULSE:** A pulse shown between the two main groups.
- DEFINITIVE IMPULSE:** A pulse shown between the two main groups.
- STOP INTERVAL (VARIABLE):** A variable duration indicated by a hatched bar at the end of the second printing stage.

tion of Delaware

Application November 14, 1935, Serial No. 49,663

17 Claims. (Cl. 178—36)

This invention relates to printing telegraph apparatus and more particularly to receiving printers responsive to isochronous code signals having a single selective current impulse.

5 The primary object of the present invention is to provide an efficient printer of simple construction operable upon the start-stop principle and comprising a minimum of operating parts.

A feature of the invention is to provide a printing apparatus having a single selector magnet which controls a toggle printing mechanism to produce a printed record in response to equal length code signals each composed of two elements of opposite signalling characteristics whose 10 individual time intervals are variable but complementary so that their summation in each code signal is equal to a predetermined time constant.

In accordance with the present invention the line signal for each character consists of a no-current starting impulse and a current definitive impulse. In the event that signal elements of 20 opposite polarity are employed, the starting impulse will be of positive or negative current and the definitive impulse will be of negative or positive nature respectively. Specifically, each code signal is composed of two signal elements in which each signal element occurs but once in a code signal. The sum of the lengths of the elements in each code signal is constant, and although 25 each element varies in length, nevertheless each element in each code signal is the complement of the other element of that particular code signal. Hence, each signal is formed and each character is determined by the relative 30 lengths of the elements composing the code signal.

Upon the reception of the starting impulse, a selector magnet, which is normally energized since the idle condition of the line is of marking or current nature, releases its armature to 35 control a power clutch, thus permitting a type wheel to rotate, which rotates in phase with a controlling element in a remote transmitter. During the rotation of the type wheel, the selector magnet, upon the termination of a starting 40 impulse which occurs simultaneously with the beginning of the definitive impulse of opposite polarity or current condition, again becomes energized and attracts and operates its armature, which action serves in the preferred form of the 45 present invention to actuate a toggle printing mechanism to effect printing at the instant when the reversal of signalling condition occurs in the code signal cycle. In another embodiment of the invention, cam actuated printing means is

employed, which printing mechanism is similarly initiated into operation at the instant of current reversal in the code signal cycle.

A better understanding of the invention may be had from the following description taken in 5 conjunction with the accompanying drawings, wherein like reference characters designate similar parts throughout the several views, and in which

5 There is indicated in the graphical representation illustrated in Fig. 1 a sequence of monopulse isochronous code signals representative of alphabetical characters, for example, "G" and "N." All code signals according to this code are of 10 uniform or equal length, each code signal consists of two elements of opposite polarity or characteristics, and each code signal comprises only a starting condition or impulse and a contiguous definitive condition or impulse. The 15 point at which the reversal of the current or characteristic nature of the code signal occurs is determinative of the identity of the character to be printed and is the point at which printing is effected.

20 As indicated in Figs. 2 and 3 a motor 11 is shown mounted on a base plate 12. It is necessary that the speed of the motor at the receiving station be regulated so that the type wheel of the printer rotates in phase with a controlling 25 element of the transmitting station. Upon the armature shaft of the motor 11 is secured a pinion gear, not shown, which meshes with a drive gear 13 loosely carried on a shaft 14, journaled at one end in a bracket 15 mounted on the base 30 plate 12, and the other end being journaled in a bracket 16 mounted on a front plate 20.

The gear 13 is frictionally connected to the shaft 14 through a pair of discs 17, 18 of frictional material compressed between flange 19 of collar 22 sleeved and splined on shaft 14 and flange 21 of collar 23 fixed on shaft 14 by set screw 23'. Compression is imparted to the friction clutch just described by a compression spring 24 positioned between sleeved collar 22 and fixed collar 22' fixed by set screw 24' adjacent bracket 15. In this manner the shaft 14 upon which type wheel 25, cam 26, stop arm 27, and star wheel 28 are fixed is given a normal urge to rotate. A selector magnet 31 is carried by a bracket 32 mounted on the base plate 12. The armature 33 of selector magnet 31 is carried upon a lever 34 pivoted at 30 to a bracket 30' mounted on the base plate 12. Lever 34 forms a part of a toggle arrangement comprising a toggle link 35 pivoted at 36 to lever 34 and at 37 to the printing hammer mechanism 42. Adjustable stops comprising eccentric screws 38 and 39 are provided to limit the oscillation of armature lever 34 controlling the toggle mechanism. Lever 34 when not attracted by the selector magnet 31 is actuated by a spring 41 extended between lever 34 and a spring post on front plate 20.

The printing hammer arrangement comprises a member 42 pivoted at 43 to the front plate 20, 60 which member is provided with a vertically extending indexing projection 44 adapted to cooperate with the notches in the star wheel 28. Member 42 also carries thereon adjacent its extremity a printing platen 45. Disposed between the platen 45 and type wheel 25 as used in Fig. 2 is a tape 46 which is guided by a suitable tape guide indicated at 47. Lever 34 is provided with a laterally disposed projection 48 which cooperates with depending arm 49 of a stop lever 50 which is pivoted at 52 to an orientation bracket 53 pivotally mounted at 54 to the front plate 20. The vertical arm of lever 51 is provided with a shoulder adapted to cooperate with stop arm 27. Lever 51 normally tends to rotate in a counterclockwise direction (as viewed in Fig. 2) due to

the action of a spring 55. With this arrangement lever 51 is held in position to arrest stop arm 27 when lever 34 is attracted by selector magnet 31. Upon deenergization of selector magnet 31, lever 34 will be actuated rightwardly by its spring 41, permitting spring 55 to rotate lever 51 out of engagement with stop arm 27. The depending arm of orientation lever 53 is provided at its extremity with an arcuate slot adapted to be adjustably positioned angularly and clamped by a shoulder screw 56. In this manner the relative position between stop lever 51 and stop arm 27 can be adjusted.

Regarding the toggle printing mechanism, the lever 34 is held attracted and engages the left stop 38 during the stop position or condition of the printer, it being assumed that the normal stop condition of the signal line is marking. In this position stop lever 51 engages the stop arm 27 and prevents shaft 14 from rotating. The platen 45 during this condition of the mechanism is held in its lower position opposite a blank space in the type wheel. At the commencement of the starting impulse of the monopulse isochronous code signal described above, the selector magnet 31 becomes deenergized and lever 34 is actuated toward its right stop 39 by spring 41. In the course of this movement of lever 34, platen 45 due to the toggle action of levers 34 and 35 is elevated momentarily and returned to its lower 30 or normal position. Printing, however, is not effected since the reciprocation of the platen 45 at this moment is performed opposite a blank space in the periphery of the type wheel. Upon reversal of current at a point or instant determinative of the character to be printed, the armature lever 34 is again attracted by magnet 31 and directed against stop 38. In the course of this movement the platen 45 due to the toggling action is again reciprocated. At this instant, 40 however, in the course of its reciprocation, the platen 45 is pressed against the proper character and at the same time projection 44 engages a notch in star wheel 28 corresponding to the character selected, thus performing an indexing operation and momentarily arresting the type wheel 45 and slipping clutch wheel 13, Fig. 3, during the production of a printed character on tape 46.

Tape feeding is performed by a cam actuated tape feed mechanism comprising tape feed cam 50 carried on shaft 14. Cam 26 cooperates with one arm of tape feed lever 57 pivoted at 58 on front plate 20; to the other arm of the tape feed lever 57 is pivoted a spacing pawl 59 which cooperates with a tape feed ratchet 61 carried on a stud shaft 62 secured to front plate 20. Lever 57 normally tends to rotate in a clockwise direction (as viewed in Fig. 2) about pivot 58 by means of a spring 63. Pawl 59 normally coacts with ratchet 61 through the instrumentality of a 68 spring 64. With the tape feeding arrangement employed in the present embodiment, the feeding or spacing of the tape is accomplished subsequently to the printing operation. Upon initiation of rotation of shaft 14 when the lever 51 and stop arm 57 are disengaged, cam 26 rotates and gradually rotates lever 57 in a counterclockwise direction against the action of spring 63 and carries the pawl 59 into engagement with the next tooth to be acted upon in ratchet wheel 61. 70 At the end of the revolution of cam 26 which is after the printing operation has been performed and immediately preceding the arrestment of stop arm 27 by lever 51, the lever 57 will drop off of the high part of cam 26 and spring 63 will 75

act to rotate lever 57 sharply in a clockwise direction, thus imparting rotation through pawl 59 to ratchet 61. This movement is imparted to a feed roller 64 fixed to ratchet 61. Cooperating with feed roller 64 is a pressure roller 65 mounted at the extremity of a lever 66 pivoted at 67 to front plate 20. Lever 66 through its spring 68 tends through roller 65 to exert pressure upon the tape 46 which, cooperating with feed roller 64, causes the tape during each spacing operation to be pushed toward the type wheel. Vertical arm 69 is provided so that pressure roller 65 may be lifted from the feed roller 64 manually for purposes of adjusting or inserting the tape 46. 15 A roll of tape 71 is mounted on the front plate 20 and the tape 46 is taken therefrom and extends over a guide roller 72 before passing between feed roller 64 and pressure roller 65. An inking roller 73 of any suitable design may be provided. In 20 the present instance the common form of roller carried on a lever 73' pivotally carried by the front plate 20 is indicated.

Operation

25 In the operation of the printer mechanism just described, the motor 11 is constantly rotating in accordance with the speed of the transmitting apparatus. Through the pinion on its armature shaft the motor imparts continuous rotation to gear 13, thus through frictional connection to shaft 14, stop arm 27 is held against the latching shoulder on lever 51. Lever 51 is maintained in latching engagement during the inoperative period of the printer by the projection 48 on lever 34, which is held attracted by selector magnet 31 due to the fact that as previously alluded to, the stop condition of the signal line is current or marking.

Due to the nature of the isochronous code signal employed in controlling the operation of the forms of printers according to the present invention, the commencement of the start impulse causes the selector magnet 31 to be deenergized and permits spring 41 to actuate armature lever 34 of the toggle arrangement to its rightward position against stop 39. In response to this movement of lever 34, stop lever 51 is retracted from stop arm 27 by spring 55, permitting shaft 14 and the elements fixed thereon to rotate. As previously pointed out, the rightward movement of lever 34 does not through the reciprocation of platen 45 effect printing because in the stop position of the type wheel a blank space thereon is presented to the printing point, thus even though the rotation of the type wheel has been initiated, no contact between the platen and roller is made. During this movement of the shaft 14, the cam 28 thereon is acting to cause pawl 59 to engage the next tooth on the ratchet 61 preparatory to imparting the spacing movement to feed roller 64. At an instant in the cycle of rotation of shaft 14 determined by the particular character to be printed and evidenced by a reversal of the current in the line channel, the magnet 31 becomes energized and instantly effects the movement of lever 34 toward the left stop 38, thus causing, due to the toggling action of the printing mechanism, the platen 45 to rise and press tape 46 against the character selected, the projection 44 acting on star wheel 38 to index the type wheel momentarily for printing. It is understood that the printing is effected at the instant when lever 34 is substantially midway between stops 38 and 39 so that when lever 34 contacts with stop 38, platen 45 has been re-

trieved from its printing position and stop lever 51 has been rotated into position to subsequently arrest stop arm 27 at the conclusion of the cycle of rotation of shaft 14. At the end of the cycle of rotation, the tape feed arm 57 is actuated by spring 63 to rotate ratchet 61 to cause the tape to be fed one character space. 5

First modification

In the modified form of the invention illustrated in Figs. 4 to 9 inclusive, the selector magnet has been modified to render the toggle mechanism more quickly responsive, and the printing and tape feeding mechanism for the most part has been arranged on the inside of the front plate so that the structure may be housed by a suitable cover to expose only the type wheel and associated inking and tape propelling elements. 10 15

The framework of the printer comprises a front plate 101 and a base plate 102 rigidly united. A speed regulated motor 104 is mounted upon the base plate 102 and carries on its armature shaft 105, Fig. 8, a pinion gear 106 which meshes with a gear 107 forming the driving member of a friction clutch assembly 108 on a start-stop shaft 109 mounted rotatably in two journals, a journal block 110 and a journal sleeve 111. Journal block 110 is fixed in front plate 101. Journal sleeve 111 is screw threaded externally, and is provided with an integral hexagonal head 112. 20 Bracket 113 is fixed upon the rear face of front plate 101 and is threaded internally to receive the journal sleeve 111 which when adjustably positioned by virtue of its screw thread and its hexagonal head 112 is fixed in desired position 25 by two lock nuts 114. Gear 107 is frictionally associated with shaft 109 by means of the friction clutch assembly 108 comprising a pair of annular friction pads 116 and 117 compressed between fixed flanged collar 118 and sleeved flanged collar 119, splined on the shaft 109 by screw stud 121, compressive force being supplied by compression spring 122 abutting the splined collar 119 and restrained adjustably by set collar 123 on the distal end of shaft 109. A type wheel 125 having 30 types throughout the greater portion of its circumference but having a blank or non-printing arc and having also a hub 126 is secured by means of a set screw 127 to the front portion of shaft 109 which extends through and in front of front plate 101. Axial position of shaft 109 and type wheel 125 is maintained by abutment of hub 126 with journal block 110 and of fixed collar 118 with the head 112 of adjustable journal sleeve 111. Back of plate 101 and within the proposed 35 housing as noted above, and fixed upon the start-stop shaft 109, Fig. 8, is a cam assembly 130 comprising a sleeve having shouldered set collar 131 and bearing tape feeding cam 132, stop arm 133, star wheel 134, and spacing bushings locked upon 40 the sleeve and against the shoulder of collar 131 by clamp nut 135. 45

In Fig. 6, a selector magnet 138 is shown carried on a bracket 139 mounted on the front plate 101. The magnet 138 herein employed is constructed with a core comprised of laminated plates having pole faces formed with divergent surfaces so as to cooperate with a wedge-shaped armature 141, Fig. 5. With this form of selector magnet, a greater magnetic flux is provided and the air gap 70 between the armature and the core is minimized through a longer operating movement so as to obtain quick response and an extended angle of operation of the armature upon energization of the magnet. Armature 141 is carried by an ar- 75

mature lever 142 forming an operating toggle element of a toggle joint printing mechanism. Lever 142 is pivoted at 143 to a bracket 144 mounted on front plate 101 and due to urge of a spring 145 normally tends to rotate away from its magnet 138 to engage an eccentric adjustable back stop 146.

Pivotedly connected to the upper end of the armature toggle lever 142 is a toggle link 147, Figs. 6 and 7, which is also connected to a printing lever 148, pivoted on a fixed stud 153 and comprising a platen member 149 and an indexing member 151 each provided with an integral tubular sleeve 150, 150' respectively and united adjustably by a screw 152. The indexing member 151 cooperates with the star wheel 134 during the printing operation. Stop lever 155, carried upon an adjustable pivot post 156, has a hook shoulder 157, a retractile spring 163, and an operating arm 160 normally engaged by a projection 154 on armature lever 142 which normally holds the stop lever 155 against the tension of spring 163 to position the shoulder 157 normally in the path of the free end of stop arm 133. Orientation member 158 is rotatable upon a fixed pivot post 159 and is provided with an indicating arm 161 adapted to cooperate with suitable graduations or calibrations on front plate 101. The arm 158 may be retained in angular adjustment 30 by means of slot and screw adjustments 162 to maintain a desirable interrelationship between stop lever 155 and stop arm 133 to determine the normal stop position of the type wheel.

The tape feed pawl 168 is provided with a spring 35 172 and a cam surface which cooperates with an eccentric adjusting stop 173, the downward movement of pawl 168 being thus limited to determine definitely the spacing movement of ratchet 169. As pawl 168 moves downwardly it engages a tooth 40 on ratchet 169, rotating the ratchet until the lower extremity of pawl 168 is wedged between ratchet 169 and stop 173. A tubular stud 170, Figs. 5 and 9, is fixed in front plate 101 and provides a bearing for a tape feed shaft 171 upon the back end of which is fixed the tape feed 45 ratchet wheel 169 and upon the front end of which is fixed a tape feed drum 175. To maintain ratchet 169 in its set position while pawl 168 is retrieved to engage the next tooth, a friction drag in the form of a spring washer 174 is provided which acts as a deterrent. A tape pressure roller 176 on arm 177 pivoted at 178 on the back 50 face of front plate 101 and passing through an opening 180 in front plate 101 is acted upon by a spring 179 to impart pressure to the tape 164 between feed drum 175 and pressure roller 176.

Operation of first modification

The improved telegraphic receiving printer is 60 illustrated in Fig. 6 in normal condition of inaction while connected to an operative but non-operating transmission control channel. Current in a closed circuit transmission circuit not shown holds the signal responsive receiving magnet 138 in energized condition, retaining its armature lever 142 in attracted position; the printing arm 148 is held down by toggle link 147; the stop lever 155 is held by engagement of projection 154 and arm 160 to maintain its hook shoulder 157 in the path of stop arm 133; the stop arm 133, shaft 109 with cam 132, star wheel 134, and type wheel 125, Fig. 8, are held against rotational urge of the operative motor 104 through friction clutch 108. The tape feed mechanism rests with follower 165 at the nadir of cam 132.

When the selector magnet 138 becomes de-energized upon reception of a starting impulse, Fig. 1, the toggle lever 142 which carries the armature 141 will be released and will respond to the tension of its spring 145 to move into engagement with its stop 146. Pursuant to this movement of lever 142, stop lever 155 will respond to the tension of its spring 163 to effect the withdrawal and disengagement of its hook shoulder 157 from the extremity of stop arm 133, thus 10 effecting release of shaft 109 and the operating elements thereon to be initiated into rotation by motor 104. At a subsequent instant of current reversal in the code signal, the armature toggle lever 142 will again be actuated magnetically to 15 its attracted position as shown in Fig. 6 and substantially at the midway points of its travel from stop 146 to magnet 138, the platen 149 will be pressed against a selected character on type wheel 125 to effect printing on the tape 164 (Fig. 4), during which time the indexing member 151 will engage a notch in the star wheel 81 corresponding to the position of the selected character. This condition, however, is only effected momentarily, and as the lever 142 continues in its responsive 20 movement under attraction of magnet 138, the platen 149 and indexing member 151 will be lowered to inoperative position, as shown in Fig. 6. The shaft 109, however, continues to rotate until stop arm 133 again engages shoulder 157 30 which has been returned into its path by projection 154 acting upon arm 160 and lever 155 during the printing operation of armature lever 142.

During the cyclical operation of the shaft 109, 35 the tape feeding cam 132 thereon is rotated and during its rotation acts to rock the tape feed cam follower lever 165 clockwise. Thus the tape feed pawl 168 is raised into position to engage the next tooth on tape feed ratchet 169, pawl 168 is urged into cooperative engagement with ratchet 169 by a spring 172, and after printing, and just before shaft 109 completes its cycle, the apex of cam 132 passes its follower 165 and spring 167 is permitted to rock the follower 165 counter-clockwise, propelling pawl 168 through its return movement and driving ratchet 169 through an angle measured by one of its teeth, thus propelling the tape 164 into position to receive the impression from the next selected type on wheel 125. As in the first form of printer described, the platen 149 is reciprocated vertically during either the backward or forward movement of armature toggle lever 142, but due to the provision of a blank space upon the periphery of the type wheel 125 opposite the printing platen 149 when the type wheel is in its stop position, printing is not effected upon the reception of the starting impulse when the type wheel 125 is still motionless.

Second modification

The embodiment of the invention shown in Figs. 10 to 19 inclusive contemplates a change in the form of toggle printing mechanism wherein the toggle levers are operated mechanically 65 under electromagnetic selective control instead of directly by power of the selector magnet as in the previous structures described. In this form of the invention, the actual printing operation is performed by a spring, the selector magnet serving merely to trip a latch to release the power stored up in the printing spring. A motor control device also is disclosed in connection with the design of the second modification. A yielding 70 75

articulation is provided between the source of printing power and the point of printing impact.

According to Figs. 10, 11, and 12, the printer structure comprises a synchronous or speed regulated motor 231 mounted on a base plate 232. The armature shaft of motor 231 carries thereon a pinion gear (not shown) which meshes with a drive gear 233 carried on a shaft 234 having one end journaled in a bracket 235 mounted on a front plate 236. The other end of the shaft 234 is journaled in front plate 236 and extends beyond front plate 236 and supports at its outer extremity a type wheel 237. Fixed to shaft 234 on the rear of front plate 236 are a star wheel 238, tape feed cam 239, and a stop arm 241 (Fig. 11).

Integral with gear 233 is a collar or sleeve portion 242 having formed thereon a threaded portion 243 which is a part of a motor control device associated with the present structure and which will be described hereinafter. Threaded portion 243 terminates in a flange 244. The assembly comprising gear 233, collar 242, and portions 243 and 244 is loosely mounted as a sleeve on shaft 234 and is frictionally connected with the shaft through the instrumentality of a friction clutch comprising friction discs 245 and 246 and flanged collar 247. The friction disc 245 in the present embodiment is interposed between collar 244 and star wheel 238, and compressive force is imparted to the assembly just described by means of a compression spring 248, interposed between member 247 and a collar 249 fixed adjustably to shaft 234.

Having reference to Fig. 12, a selector magnet 251 is carried on a bracket 252 mounted on the front plate 236. Pivoted at 253 to a sub-bracket 254 carried on bracket 252 is an armature lever assembly generally indicated as 255. Assembly 255 comprises a depending armature 256 which cooperates with magnet 251 and a bent arm portion 257. To arm 257 is secured one end of a spring 258, the other end being attached to a spring post 259 mounted on front plate 236.

Pivoted at 261 to a bracket 262 mounted on front plate 236 is an arm 263 of a toggle-joint printing mechanism, the upper end of arm 263 being pivoted to a link 264 connected between lever 263 and a printing arm assembly indicated generally as 265. Attached to toggle lever 263 is one end of a printing spring 266, the other end of which is attached to a spring post, not shown, mounted on front plate 236. Toggle lever 263 is provided with a laterally disposed portion 267 adapted to cooperate with a pair of latches 268 and 269. Latch 268 is pivoted to the lower end of the depending arm 271 of a bell crank assembly 272 pivoted at 284 and tends to rotate normally counterclockwise (as viewed in Fig. 12) due to the action of a spring 273. Latch 268 is provided at its outer extremity with a shoulder 274 which coacts with lateral portion 267 of toggle lever 263. Latch 269 is pivoted on a stud 275 fixed to the front plate 236 and tends to rotate normally in a counterclockwise direction by a spring 276 (Figs. 15 and 17). Latch arm 269 is provided at its outer extremity with a shoulder 277 and is adapted to cooperate under certain predetermined operating conditions with lateral portion 267 of toggle lever 263. Bell crank 272 is provided with a horizontal arm 278 terminating in a shoulder 279 which cooperates with the cam 239 fixed to shaft 234.

A laterally disposed lug 281, Fig. 15, on armature assembly lever 257 cooperates with a notch 282 in the upper edge of latch arm 268 to hold

lever 272 in its position against tension of a spring 283.

The printing arm assembly 265, as shown in Figs. 13 and 14 is pivoted on a stud 286 mounted on the front plate 236 and comprises a U-shaped portion 287 having a projection 288 extending through the front plate 236 so as to coact with the type wheel 237, thus functioning as a platen. Printing arm arrangement 265 also comprises a substantially U-shaped portion 289 having one arm 291 pivotally connected to link 264 of the toggle mechanism and another arm 292 terminating in a vertical projection 293 (Fig. 12) which cooperates with the notches in the star wheel 238. The portions 287 and 289 of the printing arm arrangement 265 are yieldably connected by a compression spring 294 and a screw 295.

The assembly 272 also carries on its arm 278 an orientation arrangement comprising a screw portion 296 carrying at its lower extremity a stop element 297 which cooperates with the stop arm 241 fixed to the shaft 234. With this orientation arrangement, the angular stop position of stop arm 141 may be adjusted by varying the position of stop element 197 to definitely determine the proper position of the type wheel at its normal position with respect to the timing of the code signals.

Pivoted connected to arm 271 of lever 272 is a tape feed pawl 298 which cooperates with a tape feed ratchet 299. Pawl 298 is held in operative relation with ratchet 199 by means of a spring 301. The tape feed arrangement in the presently described structure is similar to that shown in Fig. 9, the pawl 298 being provided with a cam portion adapted to cooperate with an adjustable eccentric stop screw 302 to definitely determine the spacing movement of the tape, a detent friction washer 303 being provided to maintain the spacing ratchet 299 in its stepped or advanced position. Secured to the tape feed shaft 304 is a tape feed roller 305 (Fig. 10) which cooperates with a pressure roller 306 actuated through a lever 307 by a spring 308 to effect the spacing movement of the tape 309.

Operation of second modification

In its non-operating or waiting condition, the mechanisms just described assume the positions shown in Fig. 12, wherein lug 281 (Fig. 15) on lever 257 holds lever 272 against the tension of spring 283. Cam 239 has passed its follower 278 and preparation to respond upon the reception of a starting impulse is provided by tension of spring 283. When, then, a starting impulse is received, the magnet 251 becomes deenergized and armature lever assembly 255 rotates in clockwise direction in response to the tension of spring 258, thereby disengaging lug 281 from notch 282, whereupon lever 272 is rotated about its pivot 284 until shoulder 279 contacts with the low portion of cam 239 (Fig. 16). This action of lever 272 upon latch arm 268 will cause, through the coaction of lug 267 and shoulder 274, a backward movement of toggle lever 263 against the action of spring 266. An eccentric stop member 285 is provided to limit the back movement of toggle arm 263. When toggle lever 263 has been actuated to its backward position, lug 267 thereon is engaged by the shoulder 277 of latch arm 269, the latch arm 269 serving in this manner to hold toggle lever 263, and hence the toggle printing mechanism, in its backward position of preparation to print, against tension of printing spring 266 as shown in Fig. 16.

As is understood, the movement of the toggle lever arrangement will cause the printing arm arrangement 265 to oscillate. Spring 283 acting through arm 271 and member 297 has disengaged member 297 from stop arm 241, thus permitting the type wheel 237, star wheel 238 and cam 239 to be driven by power of motor 231. At the instant of reversal of current indicative of the character to be printed, the magnet 251 becomes reenergized and causes armature assembly 255 to rotate counterclockwise, whereupon the lug 281 will act to force both latches 268 and 269 downwardly to disengage shoulder 271 from lug 267 and to prevent the engagement of lug 267 with shoulder 274 as the toggle lever 263 is actuated sharply toward its forward position by the printing spring 266. This operative position is shown in Fig. 17. As in the previous models described, printing is effected at a point substantially midway between the leftward and rightward positions of toggle lever 263, when the platen 288 is impressed against the type wheel and the projection 293 cooperates with the notch in star wheel 238 corresponding to the character selected, to index the type wheel and arrest the said type wheel momentarily to produce a clearly printed record.

With the yieldable connection of spring 294, any variation and distance between the type wheel 237 and toggle link 264 is taken up by the spring 294. For example, during the printing stroke of the toggle mechanism, the platen 288 may bear against the type wheel 237, and to prevent damage to the printing structure the toggle arrangement in straightening out may force the portion 289 upwardly against the action of spring 294 and only so much movement of platen 288 as is needed to press against type wheel 237 is imparted to portion 287.

40 Motor control

A motor control mechanism of "open line" nature comprises a traveling cam follower arm 311, Fig. 19, pivotally carried on an extension 312, Fig. 12, on armature lever 255 cooperating with the screw threaded portion 243 of collar 242 integral with power wheel 233 which rotates continuously as long as motor 231 is energized. As long as the signal receiving magnet 251 remains energized, the arm 311 will not engage with screw thread 243. In the event that magnet 251 becomes deenergized and remains so for a time greater than a predetermined time interval, say one second, the tip of the arm 311 will be moved into engagement with screw thread 243 by rotation of armature assembly 255, Fig. 12, upon release by magnet 251 and will be permitted to travel along the screw thread 243 to ultimately open a pair of contacts 313 to open the electrical circuit for the motor 231. To start the motor, upon closing the line circuit and energizing magnet 251, the armature assembly 255 will be rotated to cause the disengagement of lever 311 from the spirally conformed portion 243 of sleeve 242, whereupon a spring 314 will act to translate the arm 311 toward its normal or leftward position, as viewed in Fig. 19, to permit the contacts 313 included in the motor circuit to close to thereby start the motor. During normal telegraphic transmission operations, the extremity of arm 311 is permitted to engage its spiral cam 243 at receipt of every spacing signal impulse, but the length of the spacing periods or intervals in the code signals is insufficient to permit a prolonged engagement of arm 311 with spiral 243 to stop

the motor, and each movement or oscillation of armature assembly 255 responsive to a marking signal in the line channel will cause the disengagement of the traveling screw follower tip and the return of follower arm 311 to its ineffective position by spring 314. A motor control system such as here described is known as an "open line motor stop."

Third modification

The embodiment of the invention disclosed in Figs. 20 to 23 contemplates a printing telegraph receiver provided with a mechanical printing mechanism magnetically controlled and the substitution of cam printing for toggle printing. According to Fig. 21, a speed regulated motor 315 is mounted on a base plate 316. The armature shaft of motor 315 carries a pinion gear 315' which meshes with a drive gear 317 rotatably carried on a shaft 318 journaled in a bracket 319 mounted on a front plate 321. Gear 317 is frictionally associated with shaft 318 through the instrumentality of a friction clutch comprising annular friction members 322 and 323 compressed between gear 317 and a pair of flanged collars 324 and 325. Fixed to shaft 318 are a type wheel 326, (Figs. 20, 21), a stop arm 327, Fig. 22, and a cam 328. Juxtaposed to stop arm 327 and adapted to have a slot and locking screw adjustment therewith, is a ratchet wheel 329.

Positioned above bracket 319 is a selector magnet 331 carried upon a bracket 332 mounted on front plate 321. An armature 333 for magnet 331 is carried upon an armature lever 334 pivoted at 335, tensioned by spring 336 and adjusting screw 337 and having an arm 338 cooperating with stop arm 327. Secured to arm 338 is a spring member 339, and interposed between spring 339 and arm 338 near the lower extremities thereof is a stud 341 carried at the upper extremity of a catch 342 having a shouldered portion 343 which cooperates with the teeth on the ratchet wheel 329 to initiate the printing operation. A portion of the periphery of ratchet wheel 329 adjacent the stop position thereof is devoid of teeth, which space is representative of that portion of the type wheel provided with a blank space. Catch 342 is pivotally supported on a stud 344 carried by a lever 345 pivotally mounted at 346 to the front plate 321. Catch 342 is also provided with a depending arm 347 adapted to cooperate with a stud 348 carried on a pawl member 349 pivoted at 351 to a vertical lever arm 352, which in turn is pivoted at 353 to front plate 321. Lever arm 345 and pawl 349 are interconnected by a spring 354. The pawl 349 cooperates with a multi-tooth cam member 355 carried on a stud shaft 356 mounted on an adjusting plate 357 adapted to be adjustably positionable on front plate 321. Disposed above cam 355 is a printing arm 358 pivotally mounted at 359 on front plate 321. Printing arm 358 is provided with a cam follower 361 which coacts with the ratchet-like cam projections on cam 355. Printing arm 358 is also provided with laterally disposed platen 362 which is adapted to extend through front plate 321 so as to be operably disposed beneath type wheel 326. Printing arm 358 normally tends to rotate in a counterclockwise direction (as viewed in Fig. 22) due to the action of a spring 363.

Cooperating with cam 328 is the horizontal arm 364 of a bell crank assembly 365 pivotally mounted at 366 on front plate 321. The extremity of the depending arm 367 of lever 365 is connected

to a spring 368 which spring imparts clockwise rotation to lever 365. Pivoted to arm 367 in proximity to its lower extremity is a latch member 369 having the end of one arm provided with a shoulder 371, the end of the other arm being secured to a spring 372. The upper edge of member 352 is provided with stepped portions 373 and 374 to cooperate with latch arms 369 and 345 respectively.

10 Also pivotally carried on arm 367 of lever 365 adjacent lever 369 is a feed pawl 375 which cooperates with a tape feed ratchet 376, and an adjustable eccentric stop 377 in the manner previously described in cooperation with tape feed rollers 378 and 380 (Fig. 20) will cause the stepping of the tape 381.

Operation of third modification

In operation the relative position of the parts shown in Fig. 22 is that assumed during the stop condition of the apparatus wherein the synchronous or regulated motor 315 is continuously running and the selector magnet 31 is energized due to the marking or stop condition of the signal line. In this position the armature lever 334 is held attracted by magnet 331 so that arm 338 is positioned to arrest the stop arm 327, thus restraining shaft 318 against rotation through its frictional interconnection with gear 317. At the beginning of the start impulse the magnet 331 is deenergized and the armature lever 334 is actuated by spring 336 to effect the disengagement of arm 338 from stop arm 327. Catch 342 is also moved out of engaging relationship with ratchet wheel 329 and stop arm 327 is free to rotate. This rotation proceeds until the occurrence of a reversal of current in the code signal representative of the character selected, at which instant the selector magnet 331 becomes energized and arm 338 is actuated to its rightward position into position to stop the arm 327 when it shall ultimately arrive thereat. In so moving arm 338, the spring 339 causes the catch 342 to be actuated so that shoulder 343 will engage a tooth on ratchet 329. Ratchet 329 continuing to rotate will, through the engagement of shoulder 343 and said ratchet tooth, cause catch 342 to be raised until stud 344 eventually abuts stop 385 (Figs. 22 and 34). The relative positions of stop 385 and stud 344 are such that when stud 344 abuts stop 385 the rotation of the type wheel 326 will be arrested momentarily with the selected character presented opposite the platen 362, thus indexing the selected character for printing. This method of indexing is analogous to the star wheel and stabber methods hereinbefore described in connection with the other modified forms of the invention. The upward movement of catch 342 causes the arm 345 to be rotated in a clockwise direction so as to disengage the extremity thereof from step 374. The extremity of arm 345 also engages the extremity of latch 369 and causes the disengagement of shoulder 371 from step 373. In response to this disengagement, arm 352 is free to be rotated by a printing spring 384, thus causing pawl 349 to be actuated in the rightward direction to rotate cam 355 a predetermined amount equivalent to the angular movement or pitch of one tooth thereon. This movement of cam 355 effects the oscillation of printing arm 358 and brings platen 362 into engagement with type wheel 326 to effect printing. The type wheel 326, as previously mentioned, has been arrested momentarily with the selected character properly indexed, through the coaction

of stud 324 and stop 385, thus preventing the printed character from becoming blurred. After the printing operation is effected, the printing arm 358 is again returned to its lower position by spring 363. As the pawl 349 is actuated rightwardly, the stud 348 thereon strikes the depending arm 347 of catch 342 and rotates catch 342 in a counterclockwise direction to effect the disengagement of shoulder 343 from the then engaged tooth of ratchet wheel 329. It is, of course, appreciated that the sequence of events which combine to effect printing and spacing, during an actual cycle of operation, occurs very rapidly.

During the rotation of cam 328 in the cycle of operation being described, the bell crank lever 365 is rotated in a counterclockwise direction, thus carrying latch 369 toward the right to effect the reengagement of shoulder 371 and step 373. Simultaneously, the pawl 375 is actuated rightwardly (as viewed in Fig. 22) to engage the next tooth on the ratchet wheel 376. Immediately prior to the termination of cycle of rotation of cam 328, the lever arm 364 drops off the high part of cam 328, thus permitting spring 368 to rotate lever 365 sharply in a clockwise direction, effecting not only the spacing of the tape through the coaction of feed pawl 375 and ratchet 376, but also the return, due to the engagement of latch 371 with step 373, of member 352 to its leftward position against the action of spring 384, thus storing up energy in spring 384 pursuant to the succeeding printing operation. The structure is thus restored to the condition shown in Fig. 22.

The printing cam 355 as previously described is mounted on an adjusting plate 357. In the arrangement shown, vertical adjustment of plate 367 is effected by means of an eccentric screw 386, and the rightward and leftward adjustment of plate 357 is accomplished by means of an eccentric screw 387. It is thus seen that a universal adjustment of cam member 355 is provided.

The present invention has been disclosed in connection with certain specific embodiments thereof but it is contemplated that such embodiments are merely illustrative and that all forms coming within the scope or range of equivalency of the appended claims are intended to be covered herein.

What is claimed is:

1. In a printing telegraph receiver, a shaft, a normally energized magnet, a toggle printing means, means responsive to the deenergization of said magnet for releasing said shaft for rotation and simultaneously preparing said printing means for effective operation, and subsequently effective upon the reenergization of said magnet for toggling said printing means to effect the printing operation.

2. In a printing telegraph receiver, a single magnet responsive to monopulse isochronous code signals comprising two elements in which each element occurs but once in a signal, each element in the signal being the complement of the other element, a toggle printing means, and means responsive to the transition from one to the other of said elements to effect the operation of said toggle printing means.

3. In a printing telegraph receiver, a single magnet responsive to equal length code signals comprising two complementary elements of different nature, a toggle printing means, means effective upon the receipt of one of said elements for preparing said means for action, and means

- effective upon the transition from one to the other of said elements to consummate the action of said means.
4. In a printing telegraph receiver, a start-stop shaft, a toggle printing means, a single magnet responsive to equal length code signals comprising two complementary elements of different nature, means effective upon the receipt of one of said elements for initiating the rotation of said shaft and for preparing said toggle printing means for action, and subsequently effective upon the transition from one to the other of said elements to effect initially the operation of said printing means and subsequently the arrestment of said shaft.
5. In a printing telegraph receiver, a single magnet responsive to equal length code signals, each signal comprising a first condition and a second condition of complementary periodic lengths, a toggle printing means, and means responsive to the transition from said first to said second condition to effect the operation of said printing means.
6. In a printing telegraph receiver, a start-stop shaft, a toggle printing means, a single magnet responsive to equal length code signals, each signal comprising a start condition and a stop condition of complementary periodic lengths, means responsive to the start condition of a signal for initiating the rotation of said shaft and simultaneously preparing said printing means for effective operation, and further means subsequently responsive to the transition from start to stop condition to effect the toggling of said printing means to effect the printing operation.
7. In a printing telegraph receiver, a start-stop shaft, a toggle printing means, a single magnet responsive to equal length code signals, each signal comprising a start condition and a stop condition of complementary periodic lengths, means responsive to the start condition of a signal for initiating the rotation of said shaft and simultaneously preparing said printing means for effective operation, and subsequently responsive to the transition from start to stop condition to effect initially the toggling of said printing means and subsequently the arrestment of said shaft.
8. In a tape printing telegraph receiver, a single magnet responsive to equal length code signals, each signal comprising a first condition and a second condition of complementary periodic lengths, toggle printing means, tape spacing means, and single means responsive to the transition from said first to said second condition to control simultaneously the operation of both of said means.
9. In a recorder, a single magnet responsive to equal length code signals, each signal comprising a first condition and a second condition of complementary periodic lengths, toggle printing means, indexing means for said printing means, means responsive to said first condition for preparing said toggle printing means for action, and means effective upon the transition from said first to said second condition to toggle said printing means to effect, under the control of said indexing means, the printing operation.
10. In a printing telegraph receiver, a single magnet responsive to a first signal condition and to a second signal condition, toggle printing means, a start-stop shaft, control means for said shaft, means effective in response to the first signal condition for toggling said printing means and for establishing a first predetermined condition in said control means, and means effective upon the transition from said first to said second signal condition to print and to establish a second predetermined condition in said control means.
11. In a recording device, a single start-stop shaft carrying in fixed predetermined operative relationship to each other a type wheel and a stop arm for controlling said shaft, a toggle printing means, a single magnet responsive to electrical signalling conditions for controlling said printing means, and means controlled by the toggling action of said printing means for controlling said shaft.
12. In a recording device, a start-stop shaft, a toggle printing means, a single magnet responsive to electrical signalling conditions for controlling said toggle printing means, and means controlled by the toggling action of said printing means for controlling said shaft.
13. In a recording device, a start-stop shaft, a toggle printing means, a single magnet responsive to electrical signalling conditions for controlling said shaft and printing means, means controlled by the toggling action of said printing means for controlling said shaft, and means carrying said last recited means for orienting said start-stop shaft.
14. In a letter-by-letter recording device, a start-stop shaft, a toggle printing means, a single magnet having an armature responsive to electrical signalling conditions for controlling said toggle printing means, means controlled by the toggling action of said printing means for controlling said shaft, a letter spacing cam carried on said shaft, spacing mechanism operated by said spacing cam, and means for limiting the action of said spacing mechanism.
15. In a printing telegraph receiver, a shaft, a magnet, a toggle printing means, means controlled by said magnet for releasing said shaft for rotation and simultaneously preparing said printing means for effective operation, and subsequently effective under control of said magnet for toggling said printing means to effect the printing operation.
16. In a recording device, a start-stop shaft, a toggle printing means, a single magnet having an armature responsive to electrical signaling conditions for controlling said toggle printing means, means controlled by the toggling action of said armature for controlling said shaft, a spacing cam carried on said shaft, and spacing mechanism operated by said spacing cam.
17. In a recording device, a start-stop shaft, a toggle printing means, a single magnet having an armature responsive to electrical signaling conditions for controlling said toggle printing means, means controlled by the toggling action of said armature for controlling said shaft, a spacing cam carried on said shaft, spacing mechanism controlled by said cam, and means for rendering said cam effective for substantially one complete rotation of said shaft to prepare said spacing mechanism for effective action.

WALTER J. ZENNER. 70
